DESIGN FOR AN APPLIQUÉ

Fred Hegner, New York, N. Y.

Application February 5, 1944, Serial No. 112,446

Term of patent 3½ years

(Cl. D3—9)

To all whom it may concern:

Be it known that I, Fred Hegner, a citizen of the United States of America, residing in New York city, county of New York, and State of New York, have invented a new, original, and ornamental Design for an Appliqué, of which the following is a specification, reference being had to the accompanying drawing, forming part thereof, wherein,

Figure 1 of the drawing is a plan view of an appliqué, showing my new design.

Figure 2 is an enlarged sectional view taken on line 2—2 of Figure 1 showing the front portion of a flower as raised from the flat surface of the appliqué.

The design is shown against a dark background to bring out the details thereof.

I claim:

The ornamental design for an appliqué, substantially as shown and described.

FRED HEGNER.
